UNITED STATES PATENT OFFICE.

FRANK H. OBER, OF DENVER, COLORADO.

PERCUSSION-DRILL.

SPECIFICATION forming part of Letters Patent No. 241,705, dated May 17, 1881.

Application filed February 21, 1881. (No model.)

To all whom it may concern:

Be it known that I, FRANK H. OBER, a citizen of the United States, residing at Denver, in the county of Arapahoe and State of Colorado, have invented certain new and useful Improvements in Percussion-Drills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, in which—

15 Figure 1 is a side elevation, showing the hammer and drill in operation, the successive positions of the hammer being shown in dotted lines. Fig. 2 is a front elevation. Fig. 3 is a plan view. Fig. 4 is an enlarged section through the bearings. Fig. 5 shows an enlarged front and back view of the hub and parts of the arms. Fig. 6 is an enlarged vertical section of the drill-carrier. Fig. 7 shows enlarged perspective views of the two sections of the drill-socket. Fig. 8 is an enlarged view of the pawl and ratchet for rotating the drill-socket. Fig. 9 is an enlarged vertical section through one of the hammers, showing the manner of its attachment to the rod. Fig. 10 is an enlarged perspective view, showing a hammer-rod and clamping device. Fig. 11 is an enlarged top view of one of the hammer-bearing arms, showing the position of the hammer and its rod at the time of striking the drill and its subsequent movement to one side. Fig. 12 is an enlarged front view of the hammer in the position shown in Fig. 11.

My invention relates to that class of drills known as "percussion rock-drills," and is intended for prospecting purposes, and has for its object the production of a drill which shall be simple in construction and strong in every part, with the wearing parts easily renewed, with the minimum of weight, so as to be easily transported from place to place; and it consists in the construction and operation of parts hereinafter more fully shown and described.

A represents a vertical metal cylinder secured to a platform, B, of suitable dimensions, preferably of sufficient size to permit the operator to stand upon it while operating the crank. Into this cylinder is placed a neatly-fitting central post, A', vertically adjustable by means of

a set-screw, a', and sustaining a clutch, C, provided with vertical arms c c, affording bearings for the shaft E. The shaft E carries a crank, 55 E', on one end and a hub with two arms, F F, on the other. The crank and hub are fitted on feathers c' c', and held up to the arms c c by nuts and washer.

The hub and arms F F may be made in one 60 piece of metal or in separate pieces joined together by any suitable means. The hub may carry two or more arms, as may be desired; or, in lieu of the arms, a wheel or a disk of metal may be used with the triangular head or its equivalent.

The arms F are of suitable uniform length, and terminate in a head, F', of suitable form and size, preferably triangular, so as the more readily to adjust a slotted plate, f, which is 70 bolted to the head, so as to give the slot an angle of about thirty-five degrees divergence from a perpendicular at the time the hammer G strikes the drill-head.

The hub is provided with two depressions, 75 f' f', one on each side of the shaft, for holding the ends of the hammer-rods g g, which may be made of any suitable elastic metal. The ends of the hammer-rods are upset, forming knobs that are held in the depressions f' f' by 80 means of a washer, L, that is provided with corresponding depressions, and is secured in place by the nut upon the end of the shaft. The rod g extends a suitable distance beyond the head F', passing through the slot in the 85 plate f, where it is secured by and attached to the hammer-head G by a clamp, g', of peculiar construction, and when properly set in the hub the rod will hold the hammer forward to the front end of the slot in the plate f until the 90 blow is delivered.

The clamp g' is a conical-shaped bolt terminating in a screw and nut composed of two sections, and hollowed out to receive the rod g' and its upset head. One section of the clamp 95 is shorter than the other, and is provided with a projecting flange that enters a coincident depression in the other section, when they are closed together over the head of the rod and drawn tightly into the eye of the hammer by 100 means of the nut.

A frame, D, is hung on the shaft E by means of two arms, d d, that extend from its upper end and permit the frame to have a free verti-

- cal movement for adjustment to hold the drill within an angle of forty-five degrees between a vertical and horizontal position, as may be required by the work. The lower end of the frame terminates in a broad plate, to which is bolted a drill-carrier, H , which extends to a point beneath the hammers as they descend, and is provided with a leg, h , and a projection for receiving and holding the drill-socket.
- 10 I. The leg rests upon the ground and sustains the weight of the drill-carrier. The carrier H has a circular opening, into which is set a drill-socket, I , which is a cylinder with an angular central opening having angles coincident with the angles of the series of drill-rods used. The socket is constructed in two equal parts and provided with serrated flanges at the top, which form the ratchet for engaging the pawl K . The socket is held in the carrier by two pins, 15 i , on opposite sides, that pass through the carrier and a groove extending around the outside of the socket.
- 20 The pawl K is pivoted in the center of the carrier H , with its outer arm, k , extending over the side of the carrier for engagement with the arm F , and its inner end is connected by a spiral spring to the carrier H a suitable distance from the pivotal point. A finger is hinged to the inner end of the pawl, and is held in 25 contact with the ratchet by a spiral spring attached to a pin on the pawl near its pivotal point, and to the finger near its point.
- 25 The adjustment of the pawl to control the extent of the movement of the ratchet is effected by means of a pin, h' , and a series of holes in the carrier H , that limits the forward movement of the arm k .
- 30 This device should be accompanied by a series of drill-rods of various lengths, in order to bore the various depths of holes that may be required.
- 35 The operation of my device is as follows: The platform B having been so located and leveled that the leg h rests beside the spot where the hole is to be bored, and the hammers revolve on an even axis, the drill-rod J is set in the socket, and motion given the hammers by means of crank E' , shaft E , and arms F . The descending hammer will deliver its 40 blow squarely on the head of the drill-rod, as shown by dotted lines in Figs. 1 and 11 of the drawings forming a part of this specification, and be momently checked and crowded off one side of the head of the drill-rod by the 45 arm F and slotted plate f , which continue right on in their revolution without being checked. During this movement the hammer will be forced to the upper and outer end of the slot, as shown in Fig. 12 of the drawings, 50 and will then, immediately upon leaving the drill-rod head, be carried back to the oppo-

site end of the slot, which is its normal position, by the elasticity of the rod g . After passing the head of the drill-rod the inner edge of the triangular head F strikes the arm k of the pawl K , as shown in Fig. 3 and dotted lines in Fig. 1 of the drawings, which communicates motion to the drill-socket and rotates it one or more notches, thereby turning the drill-rod before the next blow is delivered. 55 This operation is continued until the hole is deep enough or the drill-rod is sunk too low to receive the blow fairly. In the latter case a longer drill-rod is substituted and the operation continued. 70

Having thus described my invention, I 75 claim—

1. In a percussion-drill, a revolving hub having a hammer attached thereto by an elastic rod, substantially as shown and described. 80
2. In a percussion-drill, the combination, with a suitable support, of a shaft, a hub bearing an arm provided with a slotted head, and a rod provided with a hammer, substantially as shown and described. 85
3. In a percussion-drill, the combination of the rod g , having a knob, a conical hollow clamp, g' , constructed in two sections for receiving the knob, the hammer G , and a nut, all arranged and operating substantially as 90 shown and described.
4. In a percussion-drill, the combination of a hub having depressions f' f'' , with a rod, g , having an upset end, a washer, L , having depressions l , and a shaft with a nut, substantially as shown and described. 95
5. In a percussion-drill, a vertical cylinder, in combination with an adjustable center post bearing a series of rotating hammers, and a drill-holding device, substantially as shown 100 and described.
6. In a percussion-drill, the combination of the shaft E and suitable supporting devices with the frame D , drill-carrier H , socket I , and pawl K , substantially as shown and described. 105
7. In a percussion-drill, the combination of the drill-carrier H , socket I , and pawl K , extending outward to receive the blow of the head F' , and having a finger and suitable 110 springs, for the purpose specified.
8. In a percussion-drill, the combination of suitable supporting devices, a shaft, E , and arm F , having an angular head, with the pawl and ratchet of a drill-socket, substantially as shown 115 and described.

In testimony whereof I affix my signature in presence of two witnesses.

FRANK H. OBER.
